Primary Examiner — Joseph Kukella*Assistant Examiner* — Heather Wencl(74) *Attorney, Agent, or Firm* — Maier & Maier, PLLC(57) **CLAIM**

The ornamental design for a signalling apparatus, as shown and described.

DESCRIPTION

FIG. 1 is a top rear perspective view of a signalling apparatus, showing my design;

FIG. 2 is a bottom front perspective view thereof;

FIG. 3 is a top view thereof;

FIG. 4 is a bottom view thereof;

FIG. 5 is a right side view thereof;

FIG. 6 is a left side view thereof;

FIG. 7 is a front view thereof; and,

FIG. 8 is a rear view thereof.

The broken lines in the figures show portions of the signalling apparatus that form no part of the claimed design.

1 Claim, 5 Drawing Sheets(56)
